ELECTRIC OUTLET SOCKET AND PLUG

Mario Sambonet, Milan, Italy, assignor to
Italo Rizzieri, Milan, Italy

Application July 6, 1954, Serial No. 441,455

Claims priority, application Italy July 3, 1953

8 Claims. (Cl. 200—51.09)

This invention relates to an electric outlet socket and plug, and more particularly it relates to a new and improved electric service device comprising an outlet and a companion plug of the type in which the above two members of the device are designed for mechanical inter-engagement and for completing a circuit by a combination of axial and of rotational movements imparted to the plug in respect to and inside the socket member of the device.

It is an object of this invention to provide a new and useful electric outlet of the above type, having means for instantaneous closing and interruption of the current to prevent any sparking between the contacting members thereof and therefore any inconvenience and damage caused thereby, as well known by those skilled in the art.

Another object of this invention is the provision of a plug and of a socket member of new and improved construction and designed to cooperate with said plug for inter-engagement such as to prevent accidental separating of the parts by pulling on the service cord or from other causes, even if the electric circuit is interrupted, and therefore the provision of a new and improved socket and plug device which may be usefully used as a plain switch device for turning on and off current without separation and preventing accidental separating of the parts thereof.

A still further object of this invention is to provide a new and improved electric service outlet of the character referred to above which does not leave exposed any terminals which might be contacted by a user, by children and other careless ones and thus cause shock, injury and damage.

Another object of this invention is to provide an electric service outlet of the type described with a socket of such construction that a plug member partially inserted 50 thereinto may be turned from a first position in which said member may be inserted in and removed from said socket to a second position in which said socket and plug members are mechanically inter-engaged for preventing accidental separating of said parts, while the circuit is still interrupted, that may be further turned from said last named position to a third position in which certain contacting members provided thereinto cause the circuit to be completed, that may be turned back from said third position to said second position for having the said 60 circuit broken, and that comprises means for preventing accidental turning back of the plug to said first position (in which the said plug is subject to possible removal) when the interruption only of the circuit is desired.

A further object of this invention is to provide an 65 electric service outlet of the above character in which auxiliary contacting devices and members are comprised for having auxiliary wires connected thereto, particularly but not exclusively for having the metallic body of the serviced apparatus (lamp, radio or television set, electric 70 razor, electric typewriter and so on) connected to the ground for safer and better operation thereof.

2

A still further object of this invention is to provide a device of the above character wherein an alternative embodiment of the plug member according to the invention may be used as a removable wall lamp, for example, 5 i. e. for removably supporting and operating an electric lamp at the position at which the cooperating socket member is mounted, in a wall of a building, for example.

After all, it is an object of this invention to provide a new and improved electric service outlet and plug device, the parts of which are of simple construction, readily assembled and which can readily be coupled and uncoupled.

With the foregoing and other objects in view which will appear as the description proceeds, the invention 15 consists of certain novel details of construction and combination of parts and members hereinafter more fully described and pointed out in the claims, it being understood that changes and various modifications and alterations may be made in the construction and in the arrangement of parts without departing from the spirit of the invention as defined in the appended claims.

In general, I attain the above principal objects of this invention by providing a novel construction comprising a receptacle having a shaped opening, a plug having radial 25 contact arms and designed to pass through said shaped opening and into said receptacle when in one of determined first angular positions in respect to said receptacle, resilient contact surfaces inside said receptacle and arranged therein for being contacted by said contact arms 30 as said plug has been turned inside said receptacle from one of said first positions to one of determined third angular positions angularly well spaced from said first positions, and for being well detached from at least one of said contact arms as said plug is kept at one of determined second positions intermediate to said first and third positions, means for preventing said plug to be turned back from said second position to said first position except upon exerting on said plug a voluntary determined action, and a resiliently supported non-conductive member arranged on at least one of said resilient contact surfaces and arranged in respect to said surface and to the plug's contact arm designed to cooperate therewith for having said surface instantaneously detached and spaced from said contact arm and to be instantaneously inserted between said contact members.

These and other advantageous objects and features of this invention will be fully understood by a consideration of the following detailed description of a preferred form of embodiment thereof when taken in conjunction with the accompanying drawings, forming an essential component of this specification and wherein like numerals are employed to designate like parts throughout the several figures, and in which:

Figure 1 is a perspective exploded view of the plug member and the receptacle member of an electric service outlet according to one embodiment of the invention, in which the plug member is brought near to the receptacle member in said first angular position for engagement thereinto.

Figure 2 is a partially sectioned exploded side view of plug member and receptacle member, the section being taken on line 2—2 of Fig. 4.

Figure 3 is a partial side view of a modified form of embodiment of a plug member produced according to the invention and designed to support and to electrically connect a lamp;

Figure 4 is a cross-sectional view of members of Fig. 2, in which the said plug member appears as being inserted into but not mechanically and electrically connected to the said receptacle member, the said cross-sectional view being taken on line 4—4 of Fig. 2;

Figures 5, 6 and 7 illustrate in a rather diagrammatical

manner the operative parts of members illustrated in Fig. 4, in several various respective positions during the turning-on and respectively in the said third position and during turning-off of current; and

Fig. 8 is a sectional view of the embodiment shown in Fig. 1, the section being taken on line 8—8 of Fig. 4.

In general, and referring first to Figs. 1 and 2, an electric service outlet device according to this invention comprises a plug member (Fig. 1) having a handle portion 11, preferably of non-conductive material, a cylindrical plug portion 12 of non-conductive material and radial contact arms 13 and 14 of conductive material, chrome-plated brass for example, or other suitable metal or metallic alloy known in the art, radially extended from the force end of said plug portion 12, and a receptacle member (Fig. 2) formed by a casing 19 preferably of non-conductive material, having a shaped front opening comprising a central circular portion 15 designed to allow passage of said cylindrical plug portion 12 and radial slots 16 and 17 likewise designed to allow passage of said contact arms 13 and 14 respectively of same plug.

Preferably, the said contact arms 13 and 14 and the said slot portions 16 and 17 are symmetrically shaped, so that the said plug may be inserted in said receptacle in any of two first angular positions at 180° one to the other, in which the said arms 13 and 14 are aligned with said slots 16 and 17 or 17 and 16, respectively. In the forms of embodiment shown, the electric outlet device according to this invention is designed for connecting circuits comprising two conductors only, and it is therefore provided with two contact arms only. A three-phase circuit however may be connected.

In view of the described shaped opening of receptacle member and of the cross-sectional shape of the plug member comprising the said contacting arms, the said plug member 12 may be passed through said opening and inserted in said receptacle by an axially directed movement as indicated by straight arrows A upon positioning said plug in said first angular position in respect to said receptacle.

According to the gist of this invention, engaging and contacting members and parts are provided in said receptacle member for having said plug and receptacle members mechanically connected upon completion of a combined axial and rotational movement indicated by U-shaped arrows B. Said movement comprises firstly a further axial forwarding of the plug 12 inside said receptacle, overcoming a slight axial elastic opposition, then a small clockwise rotational movement and then a small axial backward movement due to said elastic opposition, i. e. the mechanical connection of said plug and receptacle member may be actuated by imparting to said plug a so-called "bayonet" action. As said plug has completed said movement B, the electric circuit is still interrupted, i. e. at least one and preferably all contact arms are still kept well spaced from the contact surfaces arranged inside said receptacle member, and which will be fully described below. For having the circuit closed, a further angular clockwise movement C must be done. By simply turning clockwise and counterclockwise said handle portion 11 of plug member the described device according to the invention may therefore be advantageously used as a plain switch, as desired for example for having the current on or off respectively without mechanical and material separation of the plug member from the co-operating socket member.

In Fig. 2 and partially in Fig. 4 a preferred construction of the plug member is shown. Referring now to said Figs. 2 and 4, the said cylindrical plug portion 12 is actuated by a tubular member of non-conductive material, of a type currently used in production of electrical devices of the kind, having an out-turned flange portion 20 made integral to the rear end thereof and designed to be removably connected to and to close the

front open end of the said handle portion 11 of the member, said handle portion being preferably constructed in the form of a hollow cup-shaped piece of non-conductive material.

Inside said tubular plug portion 12 two metallic parts 21 are symmetrically constructed and arranged, in Fig. 2 only one of said parts 21 being shown. Any one of said parts 21 is provided with a fore radial extension forming the said radial contact arm 13 (or 14), with a rear radial extension 22 bearing a screw 23 for connection to a conductor at the terminal of the service cord leading to the serviced electric supplied apparatus. The said parts 21 are kept in the described arrangement and electrically insulated by co-axial core members 24 and 25 of non-conductive material, provided with longitudinal recesses for said parts 21 and with head out-turned flange forming portions 26 and 27, respectively, on which the end portions 22 and 13, respectively, of said parts 21 abut. Said core members 24 and 25 are firmly connected head-to-head in their abutting relationship with said parts 21 by an axially arranged metallic rod 28 having an enlarged head portion 29 positioned outside of and abutting on the external flanged end 27 of the core member 25 and having a screw-threaded portion at its other end, on which a nut 31 may be tightly screwed.

As shown particularly in Fig. 2, the said portions and parts 22, 23 and 31 are arranged and protected inside the hollow cup-shaped handle forming portion 11 of the plug member of the device. The said portion 11 is further provided with a central hole 30 designed for passage of the end portion of a conventional service cord the wire conductors of which may be firmly mechanically and electrically connected to the parts 21 by means of said screws 23. A third wire conductor comprised in said cord, if any, may be connected to said rod 28 by means of the said nut 31, for grounding the metallic frame or body of the serviced electrical apparatus. The terminals of said apparatus may therefore be electrically connected to the one and respectively to the other of said contact arms 13 and 14 and the frame structure or body thereof may be electrically connected to the externally arranged head 29 of said rod 28.

According to the alternative form of embodiment of said plug member, shown in Fig. 3, in lieu of said cup-shaped handle forming member 11 a tubular member 61 of non-conductive material is provided and connected to an out-turned flange portion 63 of a tubular plug portion 12 having contact arms as above described in referring to Fig. 2. By means of extensions 62 of said flange portion 63 a threaded socket 70 may be firmly supported inside said tubular member 61, said socket being designed for having a conventional electric bulb or glow lamp (not shown) screwed in, according to the present day equipment. Said screw-threaded socket 70 is electrically connected to one of said contact arms 13 or 14 of the plug portion and the other one of said contact arms is electrically connected to a member 64 of conductive metal or metallic alloy arranged inside and at the bottom of said socket 70 and designed for axial abutment and electrical contacting relationship with the centre terminal of the glow lamp.

Plug members produced according to the invention and constructed as shown in Figs. 2 and 3, respectively, may be alternatively connected for operation to a receptacle member of the type which will be now described in detail and which is shown in Figs. 2 and 4 to 8, in which the parts appertaining to the plug member cooperating therewith may be indiscriminately referred to either of said alternative forms of embodiment.

According to Figs. 2 and 4, the said receptacle member 10 is formed by a cup-shaped piece of non-conductive material, having a front face forming portion 40 at the centre of which the said opening 15-17 is provided. Said opening is surrounded by an externally screw-

threaded collar 41 the axial dimension of which is less than the spacing between the radially extended contact arms 13 and 14 of the plug members designed to co-operate therewith and the flange portion 20 or 63 of said plug (see Fig. 2 or 3 respectively). About said collar 41 an annular member 42 may be screwed on, if desired, for having a glass or other material-made optional covering plate 43 secured upon said front face portion 40 of the receptacle body.

The various contact surfaces and other operative devices which are arranged inside said receptacle body are preferably supported by a circular plate 44 of non-conductive material removably positioned inside said receptacle body and firmly connected thereto by means of two or three screws, for example, in abutting relationship with an internal step 45 provided in the side walls of said body. Said circular plate 44 actuates a partition dividing the interior of said body in a fore chamber (between said plate and the face forming portion 40 of said body 10) in which all contacting and circuit breaking devices are housed, and in a rear open chamber in which the several means for connection to electric current supply conductors and to the optional grounding conductor are arranged.

In the form of embodiment shown and as it may be clearly understood by a particular consideration of Figs. 2 and 4, the inner operative devices comprise a first resilient contact member 46 electrically connected to a first binding-screw 47, an oppositely arranged second resilient contact member 48 electrically connected to a second binding-screw 49 and an auxiliary axially arranged third resilient contacting member 50 electrically connected to a third auxiliary binding-screw 51 (Fig. 2). While the said contacting members 46 and 48 and the binding-screws 47 and 49 respectively connected thereto are arranged respectively inside and outside said partition forming member 44, for having a simple construction of the device the said auxiliary contacting member 50 may be supported outside said partition 44, as shown in Fig. 2, the said partition forming member 44 being provided with a central opening through which the end portion of said contacting member 50 is exposed inside said member 44 facing the opening 15 of the receptacle.

Said contacting member 50 is made in the form of a bent strip of resilient conductive metal and it is arranged and shaped, as shown in Fig. 2, to be contacted by the enlarged head portion 29 of said metallic rod 28 of the plug member as the latter is axially inserted in direction A (Fig. 1) through the said opening 15-17. The contact between said parts 50 and 29 occurs before the contact arms 13 and 14 are fully passed through the slots 16 and 17, so that during the end portion of the forward motion in direction A of the plug 12 a resilient opposition by said member 50 occurs. Further, as the said plug is nearly fully inserted in the receptacle and upon connection of rod 28 to the frame or body of the serviced apparatus and of binding-screw 51 to ground, the said apparatus' body or frame is properly grounded.

About the said opening 15 and on the inner face of collar 41 small projections 65 made integral with said collar are provided near the sides of said slots 16 and 17 (Fig. 2). For having the said plug 12-14 free to rotate inside the receptacle, it is therefore necessary to prosecute the axial forwarding motion of said plug in direction A, overcoming the opposition of resilient contacting member 50, until the rear edges of said contact arms 13 and 14 may pass over the said projections 65. As said condition is satisfied, said plug may be rotated and, as said contact arms 13 and 14 pass over said projections, the said plug may be slightly moved outwardly in direction opposed to A by the spring action of said contacting member 50. At this point the said second position is attained, as the two plug and receptacle members become mechanically inter-engaged, and the said

plug may be rotated in direction C (to the said third position) or opposed to C (back to second position) in the angular space defined by the abutment of contact arms on said projections 65, which act as stop members preventing said plug from reaching the said first position in which the mechanical inter-engagement is no more made sure and from which said plug may be drawn from the socket. When it is desired to have the plug removed from the receptacle, by a slight rotational forcing on the external handle portion 11 of the plug member, the said contact arms 13 and 14 may be passed back on the projections 65, which are preferably round shaped, as shown in Fig. 2. If a more positive prevention of accidental turning back of the plug member until the first position is desired, said projections 65 may be shaped to have sharp step forming flanks or saw-tooth shaped, so that a positive pushing action on the plug handle must be exerted for having the said contact arms free to be rotated over said projections.

Preferably, one of the contacting members designed to co-operate with the contact arms of the plug is made for having the said plug resiliently kept in the said second and third positions, and the other one is associated with the said device provided for having the circuit instantaneously closed and broken. As shown in Figs. 4 to 7, the contacting member 46 is actuated by a strip of resilient conductive metal and it is provided with a recess portion 52 designed to comprise the outer edge of a contact arm 14 (or 13) as said plug is rotated to 90° from the first position (Fig. 6), the said recess 52 having rounded flanks allowing the comprised contact arm to be easily moved by imparting a little rotational force to the plug. Further the said contacting member is shaped at both its side portions (in respect to recess 52) to abut on the contact arm 14 (Figs. 5 and 7) as soon as the said plug is rotated from its first position to its second position, and to resiliently urge the said arm in the second position, i. e. in the abutting relationship with the inner flank of one projection 65.

The second contacting member 48 is also actuated by a bent strip of resilient conductive metal, and is arranged in opposition to the said first contacting member 46. The contacting surface of said member 48 is partially covered by a flat member 53 made of non-conductive material and provided with an opening 54 positioned to allow the passage of the contact arm 13 (or 14) and to have the outer edge thereof in contacting relationship with said contacting surface as the other contact 14 (or 13) reaches the recess 52 of other contacting member 46, i. e. as the said plug is put in its said third position. The said non-conductive member 53 is resiliently urged against the axis of the device by two symmetrically arranged compression working coil springs 55 and 56, or by other equivalent spring means, and the ends of same non-conductive member 53 slidably abut on inclined surfaces 59 and 60 of non-conductive portions 57 and 58, respectively, made integral with the structure of the receptacle, preferably with the said member 44, the said portions 57 and 58 acting further as stop members for confining the movement of said non-conductive member 53 urged towards the device's axis by said spring means 55 and 56.

By a consideration of Figs. 4 to 7 the operation of the described device and the advantages thereof may readily be understood by those skilled in the art:

In Fig. 4 the plug member appears in the "first position," i. e. the contact arms 13 and 14 thereof appear in aligned relationship with the slots of the front opening of the receptacle. In such position neither electrical nor mechanical inter-engagement occur and the plug may be freely removed from the receptacle by plain pulling action exerted on the handle portion thereof in a direction opposite to A (Fig. 1). As above described, the condition of mechanical inter-engagement occurs in the said "second position," in which said contact arms have been

passed beyond the projections 65 (Fig. 2). In such position the plug is not subject to accidental separation from the receptacle, by pulling on the service cord, for example, or from other causes. Further, in such position the auxiliary grounding circuit is yet closed by the contacting relationship of enlarged head 29 of rod 28 of plug with the said contacting member 50 (Fig. 2) while the power circuit is still interrupted because at least the contacting member 48 does not contact any of contact arms 13 or 14 of the plug.

Supposing now that the plug is further rotated for example in direction D (Fig. 5), the contact arm 14 of the plugs contacts one of the side portions of the contacting member 46 while the other contact arm 13 presses on the surface of the said non-conductive member 53 urging it against the said contacting member 48. As soon as the edge of said contact arm 13 faces the opening 54 of said non-conductive member 53, the said "third position" is now attained and the latter member may be instantaneously brought back towards the axis of the device, and the outer edge of said contact arm 13 is therefore instantaneously brought in full contacting relationship with the contacting member 48 (Fig. 6) and the power circuit is instantaneously completed, as desired. The seating of opposite contact arm 14 in recess 52 of opposite contacting member 46 co-operates to maintain the plug in its said third position and prevents lateral thrusts on the said non-conductive member 53.

Supposing now that "turning-off" of the switch actuated by the device constructed according to the invention is desired, and that the plug is caused by the user to rotate in direction E (Fig. 7) towards its second position, the circular motion of the outer edge of contact arm 13 urges the said non-conductive member 53 to tangentially move leftwards (in relation to the embodiment shown in Fig. 7) sliding with its left end along the inclined surface 59, and pressing the coil spring 55 while the said outer edge of contact arm still contacts the surface of contacting member 48 through the said opening 54 i. e. while the power circuit is still closed. At a certain point of such movements of parts and members, and nearly at the position shown in Fig. 7, by the progressive lowering of said non-conductive member 53 (due to the sliding thereof on surface 59) and by the increasing inclination of outer edge of contact arm 13 (due to the rotation thereof) the action of the compressed coil spring 55 may insert the said non-conductive member 53 between said contact arm 13 and said contacting member 48, in a position substantially as shown in Fig. 5, positively spacing said contacting means and materially positioning a non-conductive solid material therebetween. Said movement of said non-conductive member 53 is accomplished in a substantially instantaneous manner, and the most desirable instantaneous breaking of the circuit and cutting of any spark or arc are therefore advantageously attained.

Preferably, as shown in the described figures, the above parts are symmetrically arranged in the device and the third position is made at 90° to the first position. In view of such features the electric service implement described may be operated either as a connecting means and as a simple switch by rotating the plug in the one or in the other direction, without prejudice of its operation and of its durability. Of course, while in the described figures the said contact arms 13 and 14 cooperate with the contacting members 48 and 46 respectively, said cooperation may be immaterially accomplished with contacting members 46 and 48 respectively.

While I have described and illustrated but one form of embodiment of this invention and but one modified embodiment of the plug member thereof, it will be readily understood that others can, by applying current knowledge in the art, make several alterations and changes in the construction of the device according to the invention and of the members, parts and details thereof, without

omitting features that fairly constitute essential characteristics of this invention as set forth and defined in the appended claims.

Further, an electric service socket and plug produced according to this invention might be readily further improved by adding other servicing devices and/or safety means. For example, the receptacle body may be provided with two or more sockets designed to co-operate with two or more plugs, as described. One or more fuses or other safety devices might be connected in the power and/or grounding circuits and arranged in the receptacle and/or in the plug member or members. By applying current knowledge in the art, a plug member may be devised in which a plug portion, designed to co-operate with a socket member according to the invention and preferably comprising the described parts 12, 13 and 14, may be structurally and electrically associated at its outer portion (in lieu of portion 11) to a socket for conventional plugs, to adapt the invention to the present day equipment.

Such variations, alterations and additions should and are therefore comprehended within the meaning and range of equivalents of this invention, and what I claim as new and desire to have protected by Letters Patent is:

25 1. An electric outlet of the type described, comprising a plug member having a cylindrical plug of non-conductive material, conductive contact arms radially extended from the end portion of said cylindrical plug, a conductive head axially arranged at the end of said plug, and binding means to connect said contact arms and said conductive head to power conductor connected to the serviced apparatus, and respectively to a conductor grounded to the body of the serviced apparatus; and a socket member comprising a receptacle body of non-conductive material having an opening comprising a circular centre portion and radial slots extended thereabout for passage of said cylindrical plug and of said contact arms when in one of determined first angular positions in respect to said socket member, a resilient first conductive 30 contacting member connected to ground positioned at the center of said receptacle body to abut on and to resiliently exert an axial opposition to the said plug on the conductive head thereof as said plug is axially inserted into said receptacle body through said opening, 35 power resilient contacting members connected to power wires positioned inside said receptacle body about the position of said plug as inserted thereinto and to be contacted by said contact arms as said inserted plug is rotated to a third position angularly spaced from said first 40 position, stop means co-operating with said resilient first contacting member for removably keeping said inserted plug in a second angular position intermediate between said first and said third angular position and in which at least one of said contact arms does not contact any 45 power contacting member, a non-conductive member movably supported inside said receptacle body and positioned between one of said power contacting members and the position of said plug as inserted in said receptacle body, an opening in said non-conductive member designed for passage of one of said contact arms as the said 50 plug is angularly positioned in its said third position and spring means for having said non-conductive member instantaneously inserted between said power contacting member and the contact arm contacting thereon as said 55 plug is caused to rotate from said third position towards said second position, and when said contact arm is still in contacting relationship with said power contacting member.

2. An electrical outlet device, comprising, in combination, a socket member; a plug member insertable into said socket member in a predetermined first position and turnable therein in inserted position about an axis from said first position to second and third positions; locking means provided on said plug member and on said socket member 60 for mechanically interlocking said plug member with said

socket member in said second and third positions of said plug member and for releasing said plug member from said socket member in said first position of said plug member; first contact means fixed to said plug member spaced in transverse direction from said axis and moving in a circular path when said plug member is turned about said axis; and second contact means fixed to said socket member and being spaced from said axis in transverse direction substantially the same distance as said first contact means and being located in said path of said first contact means; said second contact means being spaced from said contact means in said first and second positions of said plug member and being in contact with said first contact means in said third position of said plug member to establish an electrical contact with said first contact means.

3. An electrical outlet device comprising, in combination, a hollow socket member having a front plate formed with an opening therethrough and with at least one slot extending through said plate in transverse direction from said opening, said front plate having a rear face; a plug member having a front portion insertable through said opening into said socket member in a predetermined first position and turnable therein in inserted position about an axis from said first position to second and third positions; locking means fixed to said front portion of said plug member and projecting in transverse direction from said first position, said locking means having in a direction normal to said axis an outline matching said slot in said front plate so that said locking means are insertable through said slot in said first position of said plug member, said locking means having an abutting face substantially normal to said axis abutting against said inner face of said front plate in said second and third positions of said plug member to interlock said plug member with said socket member; first contact means fixed to said front portion of plug member being spaced in transverse direction from said axis and moving in a circular path when said plug member is turned in said stationary socket member about said axis; and second contact means fixed to said socket member and being spaced from said axis in transverse direction substantially the same distance as said first contact means and being located in said path of said first contact means in said third position of said plug member to establish an electrical contact with said first contact means.

4. An electrical outlet device comprising, in combination, a hollow socket member having a front plate formed with an opening therethrough and with at least one slot extending through said plate in transverse direction from said opening, said front plate having a rear face; a plug member having a front portion insertable through said opening into said socket member in a predetermined first position and turnable therein in inserted position about an axis from said first position to second and third positions; first contact means fixed to said plug member and comprising a locking and contact portion projecting in transverse direction to said axis from said front portion of said plug member, said locking and contact portion having in a direction normal to said axis an outline matching said slot in said front plate so that said locking and contact portion are insertable through said slot in said first portion of said plug member, said locking and contact portion having an abutting face substantially normal to said axis abutting against said inner face of said front plate in said second and third positions of said plug member to interlock said plug member with said socket member, said locking and contact portion moving in a circular path when said plug member is turned in said stationary socket member about said axis; second contact means fixed to said socket member and being spaced from said axis in transverse direction substantially the same distance as said locking and contact portion of said first contact means and being located in said path of said lock-

ing and contact portion and spaced from said locking and contact portion in said first and second positions of said plug member and being in contact with said locking and contact portion in said third position of said plug member to establish an electrical contact with said first contact means.

5. An electrical outlet device comprising, in combination, a hollow socket member having a front plate formed with an opening therethrough and with at least one slot extending through said plate in transverse direction from said opening, said front plate having a rear face; a plug member having a front portion insertable through said opening into said socket member in a predetermined first position and turnable therein in inserted position about an axis from said first position to second and third positions; first contact means fixed to said plug member and comprising a locking and contact portion projecting in transverse direction to said axis from said front portion of said plug member, said locking and contact portion having in a direction normal to said axis an outline matching said slot in said front plate so that said locking and contact portion are insertable through said slot in said first position of said plug member, said locking and contact portion having an abutting face substantially normal to said axis abutting against said inner face of said front plate in said second and third positions of said plug member to interlock said plug member with said socket member, said locking and contact portion moving in a circular path when said plug member is turned in said stationary socket member about said axis; second contact means fixed to said socket member and being spaced from said axis in transverse direction substantially the same distance as said locking and contact portion of said first contact means and being located in said path of said locking and contact portion and spaced from said locking and contact portion in said first and second positions of said plug member and being in contact with said locking and contact portion in said third position of said plug member to establish an electrical contact with said first contact means.

6. An electrical outlet device comprising, in combination, a hollow socket member having a front plate formed with an opening therethrough and with at least one slot extending through said plate in transverse direction from said opening, said front plate having a rear face; a plug member having a front portion insertable through said opening into said socket member in a predetermined first position and turnable therein in inserted position about an axis from said first position to second and third positions; first contact means fixed to said plug member and comprising a locking and contact portion projecting in transverse direction to said axis from said front portion of said plug member, said locking and contact portion having in a direction normal to said axis an outline matching said slot in said front plate so that said locking and contact portion are insertable through said slot in said first position of said plug member, said locking and contact portion having an abutting face substantially normal to said axis abutting against said inner face of said front plate in said second and third positions of said plug member to interlock said plug member with said socket member, said locking and contact portion moving in a circular path when said plug member is turned in said stationary socket member about said axis; second contact means fixed to said socket member and being spaced from said axis in transverse direction substantially the same distance as said locking and contact portion of said first contact means and being located in said path of said locking and contact portion and spaced from said locking and contact portion in said first and second positions of said plug member and being in contact with said locking and contact portion in said third position of said plug member to establish an electrical contact with said first contact means.

second positions of said locking and contact portion in said third position of said plug member to establish an electrical contact with said first contact means; and an interrupter plate made of insulating material and being mounted in said socket member opposite said second contact means and extending in a direction tangential to said circular path, said interrupter plate being formed with an opening therethrough and being movable in said tangential direction between a first position where said opening is between said first and second contact means so said contact means may contact each other and a second position where said interrupter plate is located between said contact means to shield said contact means from each other said interrupter plate having engaging faces cooperating with said locking and contact portion of said first contact means during said turning of said plug member from said third to said second position thereof to move said contact plate in said tangential direction and in the same sense as said plug member; spring means engaging said interrupter plate from opposite sides and tending to keep said interrupter plate in said first position, one of said spring means being deformed during the movement of said plug member from said third position to said second position so as to move said interrupter plate to said second position thereof at the moment of contact disengagement during the turning movement of the plug member.

7. An electrical outlet device comprising, in combination, a hollow socket member having a front plate formed with an opening therethrough and with at least one slot extending through said plate in transverse direction from said opening, said front plate having a rear face; a plug member having a front portion insertable through said opening into said socket member in a predetermined first position and turnable therein in inserted position about an axis from said first position to second and third positions; first contact means fixed to said plug member and comprising a locking and contact portion projecting in transverse direction to said axis from said front portion of said plug member, said locking and contact portion having in a direction normal to said axis an outline matching said slot in said front plate so that said locking and contact portion are insertable through said slot in said first position of said plug member, said locking and contact portion having an abutting face substantially normal to said axis abutting against said inner face to said front plate in said second and third positions of said plug member to interlock said plug member with said socket member, said locking and contact portion moving in a circular path when said plug member is turned in said stationary socket member about said axis; second contact means fixed to said socket member and being spaced from said axis in transverse direction substantially the same distance as said locking and contact portion of said first contact means and being located in said path of said locking and contact portion and spaced from said locking and contact portion in said first and second positions of said plug member and being in contact with said locking and contact portion in said first and second positions of said plug member and being in contact with said locking and contact portion in said third position of said plug member to establish an electrical contact with said first contact means; first retaining means extending from said rear face of said front plate and cooperating with said abutting face for retaining said plug member in said second position; second retaining means on one of said contact means and cooperating with the other of said contact means for retaining said plug member in said third position; and spring means mounted in said socket member, spaced from said front plate and opposite said opening through said front plate, said spring means en-

gaging said front portion of said plug member in inserted position of the latter to urge said abutting face of said locking and contact portion against said rear face of said front plate of said socket member when said plug member is in said second and third positions.

8. An electrical outlet device comprising, in combination, a hollow socket member having a front plate formed with an opening therethrough and with at least one slot extending through said plate in transverse direction from said opening, said front plate having a rear face; a plug member having a front portion insertable through said opening into said socket member in a predetermined first position and turnable therein in inserted position about an axis from said first position to second and third positions; first contact means fixed to said plug member and comprising a locking and contact portion projecting in transverse direction to said axis from said front portion of said plug member, said locking and contact portion having in a direction normal to said axis an outline matching said slot in said front plate so that said locking and contact portion are insertable through said slot in said first position of said plug member, said locking and contact portion having an abutting face substantially normal to said axis abutting against said inner face of said front plate in said second and third positions of said plug member to interlock said plug member with said socket member, said locking and contact portion moving in a circular path when said plug member is turned in said stationary socket member about said axis; second contact means fixed to said socket member and being spaced from said axis in transverse direction substantially the same distance as said locking and contact portion of said first contact means and being located in said path of said locking and contact portion and spaced from said locking and contact portion in said first and second positions of said plug member and being in contact with said locking and contact portion in said third position of said plug member to establish an electrical contact with said first contact means; first retaining means extending from said rear face of said front plate and cooperating with said abutting face for retaining said plug member in said second position; second retaining means on one of said contact means and cooperating with the other of said contact means for retaining said plug member in said third position; third contact means centrally located in said plug member, extending therethrough and being insulated from said first contact means; spring means mounted in said socket member, spaced from said front plate and opposite said opening through said front plate, said spring means made from conductive material and forming fourth contacting means and engaging said third contact means on said plug member in inserted position of the latter to urge said abutting face of said locking and contact portion against said rear face of said front plate of said socket member when said plug member is in said second and third positions and to establish a contact between said third and fourth contact means; and means for grounding said fourth contact means.
